(54) **WASHING MACHINE**

(76) Inventor: **Amos Larcum**

Ames Sparrow
Letters Patent

The Schedule referred to in these Letters Patent and making part of the same containing a description in the words of the said Ames Sparrow himself of his "improvement" in the machine for Washing Clothes.

To all to whom these presents shall come, Be it known that Amos Sparrow of the city of Troy in the County of Rensselaer and State of New York have invented a new and useful improvement in washing and Cleaning clothes and that the following is a full and exact description thereof:-

Washing Machines to which the improvement here to be described is applicable consist of a rectangular box about two feet square and two feet deep within which is placed a cylindrical drum of a length and diameter equal to the inside of the box, excepting a space between the end sides and bottom of the box and the cylinder of about half an inch. The outside of the drum is formed of flats or rounds firmly fixed to circular ends and placed about one fourth of an inch apart. The cylinder is to be suspended upon guides attached to the ends and made to rest and turn freely on metal or other boxes fixed in the box which encloses the cylinder. One of the guides should be very extended out so as to admit a crank upon the end for turning the cylinder. The top of the box which encloses the cylinder should be covered. One side of which or the whole should be made to open as a lid upon hinges or a door instead to be provided in the top to be attached with hinges. The cylinder also should be provided with a door or opening, through these openings the clothes are to be introduced and taken out. The opening of the cylinder should be about eight inches wide and the door which is to close it should be formed of flats or rounds attached at each end to a segment of a circle corresponding with the curve of the cylinder and about one inch apart from

from the corner to the concave edge. The bed for the door is to be formed by cutting down a shoulder on the inside of each head of the cylinder equal to about half its thickness so as to admit the end segments of the door and the slats attached thereto to one uniform circle with the rest of the cylinder. The ends of the segments on one side of this door and the corresponding end of the bed for each taking them from the center to the concave edge should be made to terminate in an angle of about fifty degrees so as to match in form of a dove tail on that side. While the other ends terminating in the direction of the radius of the cylinder may be a closed round fast. It is secured by a button at or near the centre of the slat. On forming the outside of the cylinder, two slats are to be placed opposite each other and a row of wooden pins, about four in each attached or fixed in perforations through the slat. The pins should be about one and one fourth of an inch in diameter extending in towards the center of the cylinder about three inches. The process of washing or cleansing clothes is this. They are placed within the cylinder the door of which is closed down and buttoned. The cylinder is then turned by the outside crank by which movement the pins take their round to such elevation as shall cause them to slice off against the opposite side of the cylinder and falling before the other row of pins they are again taken up in the same manner & so on in succession — And the movement of the cylinder is to its velocity, should be such as to produce this effect. By this process of agitation with the aid of hot water or steam or both clothes are washed & cleaned. Now the movement which is hereby attained and which is applicable to washing machines underwritten upon the principles of the foregoing description consists in the heating the water for this process by the application of steam within the machine. For this purpose a boiler of copper, tin or other suitable material is to be provided the dimensions of which may be such as to be placed over a common portable furnace of medium size or a Relation Stove as it may be.

heated in any other way at discretion. It should be covered or closed by soldering, riveting, or otherwise so as to be steam tight excepting a passage for the steam as it is generated by means of a pipe from the boiler to the machine. This may be about one and one fourth of an inch in diameter. It should be made to enter the machine box near the bottom and below the surface of the water within it so that the steam shall ^{be condensed} by and within the water and thereby subject to it the heat it contains. In order to prevent the water in the machine from running into the steam pipe to any considerable distance the pipe should approach the machine a little above say six inches or more above the level of its entrance and then descend to it by means of elbows or otherwise. A little forward of the end of the pipe within the machine an apron of wood should be placed about four inches wide. The upper edge of which should be attached to the side of the box running parallel with the cylinder and the ends of the apron fitted and attached to the respective ends of the box so as to give it in its longitudinal direction an inclination downwards of about forty-five degrees, by which the lower edge is to be brought to within about an inch and an half of the bottom of the box. This apron and the angular part thereof which is formed by it are for the purpose of forcing the steam under the edge of the apron and therefore if necessary, into the water at the bottom of the machine (admitting that it will always be more than an inch & a half deep) in case it shall have escaped being concentrated by the water as it is discharged from the steam pipe. What I claim of the above described improvement as now and may hereinafter be made is the use and application of steam within the machine for heating water for washing, cleansing or rinsing clothes by causing the steam to be concentrated by and within the water therein and by the same means increasing its temperature so as to generate steam within the same.

chine as the cleaning process may require
